UNITED STATES PATENT OFFICE.

EDWARD C. MEIER, OF PHOENIXVILLE, PENNSYLVANIA.

BOILER.

1,208,811.

Specification of Letters Patent. Patented Dec. 19, 1916.

Application filed April 30, 1915. Serial No. 24,899.

To all whom it may concern:

Be it known that I, EDWARD C. MEIER, a citizen of the United States, residing at Phoenixville, in the county of Chester and 5 State of Pennsylvania, have invented certain new and useful Improvements in Boilers, of which the following is a specification.

My invention relates to improvements in 10 boilers, the object of the invention being to provide an improved construction of boiler in which the several parts are welded together, reducing the use of rivets to a minimum in the boiler construction.

15 A further object is to provide an improved boiler in which the water legs or boxes are constructed of a plurality of parts securely welded together and dispensing with the use of rivets as connecting means.

20 A further object is to provide a boiler which is of simple inexpensive construction, and which is capable of withstanding the maximum of internal pressure.

With these and other objects in view, the 25 invention consists in certain novel features of construction and combinations and arrangements of parts as will be more fully hereinafter described and pointed out in the claims.

30 In the accompanying drawings: Figure 1 is a view in end elevation illustrating my improvements in connection with a battery of boilers. Fig. 2 is a fragmentary view in section on an enlarged scale on the line 2—2 of Fig. 1. Fig. 3 is a view in longitudinal section on the line 3—3 of Fig. 1, the accumulating tank being omitted, and Fig. 4 is a fragmentary view illustrating a modification.

40 1, 1, represent the water boxes or legs of a boiler connected by a cylinder 2, and by water tubes 3. The outer sheet 4 and the inner sheet 5 of the boxes 1 are connected by a welded joint 6, which construction 45 forms the subject matter of an application for patent executed on even date herewith, and which therefore need not be described more in detail in the present application. The sheets 4 of both boxes 1,

50 are provided with openings 7 in line with openings 8 in sheets 5. Heads 9 are projected through the openings 7, and have annular flanges 10 at their inner edges welded to the sheets 4. Nipples 11 are projected 55 through the openings 8, and have annular flanges 12 welded to the inner faces of

sheets 5. The boiler casing 2 is secured to the nipples 11 in any approved manner, but I have shown ordinary rivets 13 for the purpose.

60 Stay bolts 14 extend through the sheets 4 and 5 of boxes 1, and also through the flanges 10 and 12 of heads 9 and nipple 11 respectively. As above stated, the parts of the boxes 1 are welded together. The heads 65 9 are welded to the sheets 4, and the nipples 11 are welded to the sheets 5, so that the boxes are constructed entirely without employing ordinary rivets, and while I have shown rivets connecting the casing 2 with 70 the nipples 11, it is to be understood that this particular form of connection is immaterial as my invention resides more particularly to the construction of box or water legs and the casing 2 may be connected 75 in any approved manner.

75 In Fig. 1, I illustrate in end elevation a battery of boilers in which a steam collecting tank 15 is provided above the boxes 1, and said boxes are connected by couplings 80 16. One of these couplings is shown in detail in Fig. 2, in which it will be noted that the coupling is provided with oppositely screw-threaded ends engaging in threaded openings 17 in the boxes, and is 85 provided between its ends with a wrench receiving angular portion 18 to rigidly couple the boxes together, and insure a free flow of water from one box to the other, preventing any possibility of the filling of one box with- 90 out the other.

95 Fig. 4 illustrates a modification in which the sheets 4 and 5 are provided with outwardly projecting flanges 19 around its openings 7 and 20 respectively, so as to further strengthen the juncture with the head 9 and nipple 11. In this construction, the welding point 20 is at the outer end of the flange 19, and not at the wall of the openings.

100 In all places I have indicated the weld by the numeral 20, and as the drawings are on an extremely small scale, the welding material is exaggerated, but it is to be understood that I shall preferably weld at the 105 points indicated by the numeral 20.

110 Various slight changes might be made in the general form and arrangement of parts described without departing from my invention, and hence I do not limit myself to the precise details set forth, but consider myself at liberty to make such changes and

alterations as fairly fall within the spirit and scope of the appended claims.

Having thus described my invention, what I claim as new and desire to secure by Letters Patent is:

- 5 1. In a boiler, the combination with two water legs, both water legs having registering openings in their inner and outer sheets, heads projected through the openings in the outer water leg sheets, said heads having outwardly disposed flanges located against the inner faces of the outer water leg sheets, nipples projecting through the openings in the inner water leg sheets and having flanges 10 at their inner ends, a casing secured at its ends to the respective nipples, a plurality of stay bolts projected through both sheets of both water legs, and through the internal flanges of the heads and the nipples, substantially as described.
- 15 2. In a boiler, the combination with two water legs, both water legs having registering openings in their inner and outer sheets, heads projected through the openings in the outer water leg sheets, said heads having outwardly disposed annular flanges located against the inner faces of the outer water leg sheets, nipples projecting through the openings in the inner water leg sheets and having 20

annular flanges at their inner ends, an elongated casing having its ends located inside of and secured to the respective nipples, a plurality of stay bolts arranged in annular formation and projected through both sheets of both water legs and through the flanges of the heads and the nipples, substantially as described.

3. A boiler, comprising two boxes, said boxes having openings in their inner and outer sheets, heads projected through the openings in the outer sheets, and having outwardly disposed projecting flanges at their inner portions welded to the inner faces of the outer sheets, nipples projecting through the openings in the inner sheets and having outwardly disposed projecting flanges welded to the inner faces of the inner sheets, a casing connecting the nipples, and stay bolts projecting through the front and rear sheets and through the flanges of the heads and nipples, substantially as described.

In testimony whereof I have signed my name to this specification in the presence of two subscribing witnesses.

EDWARD C. MEIER.
